Attn:

UNITED STATES PATENT OFFICE

107,001

DESIGN FOR A SWITCH HOUSING FOR FLASHLIGHTS

Orville T. Wood, Clinton, Mass., assignor to
Blake Manufacturing Corporation, Clinton,
Mass., a corporation of Massachusetts

Application May 14, 1937, Serial No. 69,351

Term of patent 7 years

To all whom it may concern:

Be it known that I, Orville T. Wood, a citizen of the United States and a resident of Clinton, county of Worcester and State of Massachusetts, have invented a new, original, and ornamental Design for a Switch Housing for Flashlights, of which the following is a specification, reference being had to the accompanying drawing, forming part thereof.

Fig. 1 is a plan view of a switch housing for flashlights showing my new design.

Fig. 2 is a side elevation; and

Fig. 3 is an end elevation as seen from the right of Figs. 1 and 2.

I claim:—

The ornamental design for a switch housing for flashlights as shown.

ORVILLE T. WOOD.
